United States Patent Office.

WILLIAM H. CUMMINGS AND HORACE L. CHILDS, OF BOONESBOROUGH, IOWA.

Letters Patent No. 91,721, dated June 22, 1869.

IMPROVEMENT IN PLOWS.

The Schedule referred to in these Letters Patent and making part of the same.

To all whom it may concern:

Be it known that we, WILLIAM H. CUMMINGS and HORACE L. CHILDS, of Boonesborough, in the county of Boone, and in the State of Iowa, have invented new and useful Improvements in Plows; and do hereby declare that the following is a full, clear, and exact description thereof, reference being had to the accompanying drawings, and to the letters of reference marked thereon.

The nature of our invention consists in the construction of a corn-plow, and in the manner of attaching the plow-beams to the axle, and of raising the plows from the ground, as will hereafter be shown.

Figure 1 is a sectional view of our plow.

Figure 2 is a plan view of the same.

Letter A represents the axle, which is supported by the two driving-wheels B.

Passing through this beam or axle A, toward each end, are two metal rods C, to the lower ends of which are secured the plow-beams. As these rods pass loosely through, having a bolt passed through at the upper ends, so as to prevent their coming out, the plow-beams can be swung around to any desired angle.

In order to strengthen these rods C, metal braces E have been attached to the lower ends, and which are then secured to the cross-piece F extending across the tongue.

Placed in the rear of each of the driving-wheels, there is a shield, G, supported by rods, extending back from the axle, so as to prevent the plow-beams from rubbing against the wheels, as they are swung around from side to side.

Attached to the front ends of the plow-beams D, on the outer sides, there are flat metal plates, which are bent so as to pass over the rods C, and then are pivoted to them, so as to allow the beams to be either raised vertically, or moved to any desired angle. To

each one of these beams there are attached two plows and a handle, by means of which they are governed.

The brace H, attached to each of the forward or front plows, has several holes made in it, so that this plow can be raised entirely free from the earth, when not wanted.

To each one of the beams on the rear ends, there is secured a metal plate, I, which has a slot cut through it.

Secured to the tops of the rod C, are two long metal rods, L, which extend backwards over the beams, and pass through the slotted plates I. These rods have a shoulder formed upon them, so that they can be made to catch in these plates, and thus hold the plows suspended above the ground, while going to or from the fields, or while turning corners. The beams D are just far enough apart for a plow to work upon each side of a row of corn.

Having thus described our invention,

What we claim, and desire to secure by Letters Patent, is—

1. The arrangement of the bar F, braces E E, rods C C, beams D D, and rods L L, all substantially as set forth.
2. The shields or guards G, when used to protect the plow-beams, substantially as set forth and described.
3. The combination of the plow-beams D, rods C and L, shields G, braces E, and plate I, when all are used in the manner and for the purpose set forth.

In testimony that we claim the foregoing, we have hereunto set our hands, this 19th day of April, 1869.

WILLIAM H. CUMMINGS,
HORACE L. CHILDS.
